UNITED STATES PATENT OFFICE.

OSCAR J. SAXE, OF BROOKLINE, MASSACHUSETTS.

PROTECTOR FOR FASTENING DEVICES.

1,096,269.

Specification of Letters Patent. Patented May 12, 1914.

Application filed August 19, 1912. Serial No. 715,755.

To all whom it may concern:
Be it known that I, OSCAR J. SAXE, a citizen of the United States, residing in Brookline, in the county of Norfolk and 5 State of Massachusetts, have invented an Improvement in Protectors for Fastening Devices, of which the following description, in connection with the accompanying drawings, is a specification, like letters on the 10 drawings representing like parts.

The present invention relates to a cap or protector for the fastening devices employed to fasten to a floor or wall, a flanged article, such as a water-closet bowl, bath-tub, lavatory, or the like, in which the fastening devices extend through the flange.

It is the practice to make porcelain or enamel bowls, bath tubs, lavatories and similar articles with a base which extends beyond the body of the bowl in the form of a flange; and the bolts or screws which are used as fastening devices to hold the bowl on the floor and to make the waste-pipe connection, are passed through openings in the 25 said flange. It is the present practice to leave the heads of the fastening devices exposed, although, in some cases, caps have been put over them, and fastened to the face of the flange with plaster of Paris or cement, 30 the fastening in this case, however, being inadequate so that the caps are very likely to be pulled off or broken.

In the bowl chosen to illustrate the invention, the flange is provided with recessed 35 portions around the bowl openings, and the said recessed portions form pockets for the lower parts of the covers which protect the fastening devices. The said covers are larger in diameter than the recessed portions, and lie flush with the flange around 40 said recessed portions, the lower parts of the said covers, however, being smaller in diameter so as to fit and enter the recessed portions. The covers are thus held firmly in 45 place, and the joint between the covers and the flange is not only dirt and water proof, but invisible as well.

Figure 1 is a side elevation of a water closet bowl embodying the invention, a portion 50 of the flange being broken away and shown in section; Fig. 2 is a transverse sectional detail on the line x^2 of Fig. 1, looking in the direction of the arrow; and Fig. 3 is a sectional detail showing a modification.

55 The bowl a which is of any ordinary con-

struction and arrangement, is provided with the base b which extends in the form of a flange beyond the lower wall of the bowl, thus not only affording an adequate standard for the bowl, but also affording means 60 for utilizing external fastening devices at the outside of the bowl to hold the same securely upon the floor.

The flange b is provided with openings b^2 to receive the fastening devices c . If the 65 bowl is to be fastened to a wooden floor, the fastening devices are in the form of ordinary wood screws, having bolt-heads or screw-driver heads as shown, respectively, in Figs. 1 and 3, the heads bearing on the 70 flange around the openings, while the screw points engage in the wood. It is obvious that bolts and nuts may be substituted for the wood screws, if the nature of the floor is such as to require it.

In accordance with the invention, the flange is provided, adjacent to each opening b^2 , with a recess to receive a portion of a cover or closure d , so that the said cover can be fastened securely in the flange in such 80 a way as to leave a smooth exterior, without any open joint or irregular surface which is hard to keep clean. The construction is such, moreover, that the metal parts are wholly inclosed and protected.

In the construction shown in Figs. 1 and 2, the flange b is provided with a cup or depression surrounding the fastening device, the cup being deep enough to inclose the head of the fastening device, and to receive 90 the smaller projecting part d^2 of the cover d . The upper part of said cover d is of greater diameter than the cup or depression, and lies flush with the surface of the flange around the opening. In the construction 95 shown in Fig. 3, the same result can be obtained by making the smaller projecting part in the form of an annular rib d^3 which is the equivalent of the projecting part d^2 and which enters and fits an annular recess 100 b^3 formed in the surface of the flange b around the opening for the fastening device. In either of these structures, a neat 105 inclosing cover, made of material similar to that of which the bowl is formed, can be fitted and fastened in position, so that it wholly incloses and protects the metallic fastening device, leaving, moreover, a smooth and unbroken exterior with no crevices to collect dirt.

What I claim is:

A protector for a fastening device for flanged articles such as water-closet bowls and bath-tubs, which is independent of the fastening device and consists in a head one surface of which is larger in area than the fastening device, and adapted to lie flush with the surface of the flange around the fastening device; and an annular tongue of 10 smaller diameter projecting from said surface, which is adapted to enter and fit a re-

cess in the flange around the fastening device, and which has a pocket or recess for the head of the fastening device.

In testimony whereof, I have signed my 15 name to this specification in the presence of two subscribing witnesses.

OSCAR J. SAXE.
